UNITED STATES PATENT OFFICE.

CHARLES W. HUTCHINSON, OF NEW ROCHELLE, NEW YORK, ASSIGNOR OF FORTY-NINE ONE-HUNDREDTHS TO CHARLES W. NISBETT, OF FLUSHING, NEW YORK, N. Y.

WINDOW-SHADE FIXTURE.

1,114,990.

Specification of Letters Patent. Patented Oct. 27, 1914.

Application filed May 14, 1913. Serial No. 767,549.

To all whom it may concern:

Be it known that I, CHARLES W. HUTCHINSON, a citizen of the United States, residing at New Rochelle, in the county of Westchester and State of New York, have invented certain new and useful Improvements in Window-Shade Fixtures, of which the following is a specification, reference being had therein to the accompanying drawings, 10 forming part thereof.

My invention relates to fixtures for window shades, and particularly to fixtures which are constructed so that the shade is carried along part of the way with a sash as 15 the sash is opened, as for ventilation, and is then automatically released from the sash and is caught again by the sash as the sash is moved back. Such fixtures are described and claimed in my prior Patent No. 1,059, 20 964, of April 22, 1913, and the preferred construction there described comprises two guides secured on opposite sides of the window frame and having outwardly turned guide portions at their lower ends, and two 25 shade-supporting brackets screwed into sockets in opposite sides of the sash and having overhanging arms, the brackets being arranged to hold the shade spindles in the respective guides, whereby the shade spindles 30 are moved out from under the overhanging arms by the outwardly turned portions of the guides as the shade is carried down with the sash along the guides, and the shade is thus released from the brackets and is held 35 in the ends of the guides in position to be picked up again by the brackets as the sash is raised. In practice this construction has disclosed certain defects, among which has been the tendency of the spindles to bind in 40 the guides, due to their torque, the difficulty in carrying two curtains, particularly one above the other, as is the usual and preferred arrangement, and the preventing of the sashes passing each other.

45 One object of my invention is to obviate these difficulties.

Another object is to provide a construction whereby the shade may be transferred from one sash to the other, and thus permit the 50 sashes to pass.

Other objects are simplicity of construction, and convenience and reliability of operation.

Still other objects and advantages of my construction will appear from the following 55 description.

My invention comprehends shade-carrying members, such as plates, upon which one or more shades are mounted and which engage in the guides and are carried by the brackets. 60

More specifically the guides have undercut guide grooves, and the shade-carrying plates have guide-engaging members, such as guide studs, with heads shaped to engage in the guide grooves, whereby the studs are 65 secured in the grooves while being free to move longitudinally thereof.

My invention also comprehends brackets which are secured to the one sash in such manner as to be removed therefrom by relative movement between the brackets and the sash, and bracket releasing and holding members carried by the other sash in position to catch the brackets as the sashes pass and remove the brackets from the former 75 sash and hold them ready to be caught and transferred to the former sash as the sashes again pass in the opposite direction.

My invention also comprehends various other features of construction, and arrangements and combinations of parts, as will hereinafter more fully appear.

I shall now describe the illustrated embodiments of my invention, and shall thereafter point out my invention in claims. 85

Figure 1 is a vertical sectional elevation, taken on line 1—1 of Fig. 3, of the upper portion of a window sash and frame with fixtures embodying my invention. Fig. 2 is a similar view showing the sash lowered 90 and the shade released. Fig. 3 is a plan of the same with the top of the window frame removed. Fig. 4 is a front elevation of the upper left hand corner of the window and frame as shown in Fig. 1. Fig. 5 is a detail 95 in front elevation of a bracket and its supporting plate. Fig. 6 is a view similar to Fig. 1, showing a modified construction. Fig. 7 is sectional elevation of the same, on line 7—7 of Fig. 6, looking toward the right. 100 Fig. 8 is a view similar to Fig. 6, showing the sashes passed and the parts in their resultant positions. Fig. 9 is a plan of the left end of the same. Fig. 10 is an elevation of a portion of the frame and of the upper left 105 hand corner of the lower sash, the bracket

being in section on line 10—10 of Fig. 8. Fig. 11 is a detail in transverse section on a slightly enlarged scale, taken on line 11—11 of Fig. 8, as viewed from below.

5 In the embodiment of my invention illustrated in Figs. 1 to 5, each of the brackets, which are carried on opposite sides of the upper sash 1 near its top, comprises a flat metal supporting plate 2, which is secured, 10 as by screws, to the sash 1, and has two integral retaining arms 3 overhanging one edge, and a locking tongue 4 struck up from the other edge, and a releasable bracket arm 5 supported on the plate 2. The bracket 15 arm 5 has a flanged or angularly extending plate-engaging base part 6 which is arranged to engage underneath the overhanging arms 3, and pivoted to the base 6 is a bent locking lever 7, arranged to latch underneath the locking tongue 4 and secure the base 6 underneath the arms 3, thereby locking the bracket arm to the supporting plate. To remove the bracket arm, it is only necessary to raise the lever 7 clear of the 20 tongue 4 and withdraw the base 6 from underneath the arms 3. The bracket arm 5 is made extensible to accommodate it for use with windows of various dimensions, and for this purpose the arm is made in two 25 parts, one part being slotted and the other part having guide flanges, and a set screw engages in the slot and screws into the other part and locks the parts in adjusted position.

30 25 Each of the bracket arms 5 is provided near its outer end with a longitudinally extending receiving slot 8 open at its outer end and formed by bifurcating the bracket, thereby providing a short overhanging arm 40 9 and a complementary arm 10 on the under side of the slot 8, the under arm 10 being somewhat longer than the overhanging arm 9. Supported upon these bracket arms are 45 shade-carrying plates, as will now be described.

Two curtains are shown supported upon the fixtures in Figs. 1, 2 and 3, one above the other, and to receive the spindles 11 and 12 of the upper and lower curtains, respectively, a pair of curtain carrying plates 13 and 14 are provided at each end, in which are provided spindle-receiving perforations, and which are coupled together by a tongue 15 on the lower end of the upper plate 13 50 engaging in a perforation 16 in the upper end of the lower plate 14, thus permitting articulation or relative angular movement between the two plates for a purpose which will hereinafter appear. If only one curtain 55 is used, the upper plate 13 may be dispensed with, as shown in Figs. 6 and 8.

On each side of the window frame is secured a guide member 17, which has its longitudinal sides bent up at acute angles to 60 form an undercut guide groove, open at its

upper end and closed at its lower end. The 70 guide members are generally vertical, and have their lower ends curved outwardly away from the window sash, as shown. The shade-carrying plates are provided with one 75 or more guide studs 18, which are riveted and secured in perforations in the plates, and are provided with flaring plane-sided 80 guide heads shaped to fit in the guide grooves and slide freely therein, while being prevented from escaping therefrom except at the open end of the grooves. At 85 their lower ends the plates 14 are offset outwardly so as to extend over the bracket arms and the lower studs 18 are accordingly 90 elongated and are adapted to be supported upon the respective bracket arms (see Fig. 11).

In use the spindles of the lower guide 95 studs 18 engage in the respective slots 8 of the brackets, and as the sash 1 is raised and lowered within the limits of the vertical portions of the guide grooves, the shade-carrying plates and hence the shades are moved with the sash, the plates being guided by the 100 engagement of the studs 18 in the guide grooves. Preferably the shades are so proportioned in length that the spindles also extend through the plates into the guide grooves, as shown. It will be noted that 105 the torque of the spindles is received by the plates, and consequently the spindles are prevented from binding in the grooves.

The guide grooves are so disposed that 110 their vertical portions retain the lower bracket-engaging studs 18 underneath the overhanging arms 9 in the slots 8 of the bracket arms, but their outwardly turned lower ends guide the bracket-engaging studs 18 outwardly in the slots 8 as the sash 1 is 115 lowered until the studs are free of the overhanging arms 9, and the shade-carrying plates are thereby released from the brackets. The outwardly turned lower end of the 120 guide members are of such length that the bracket-engaging studs reach the ends of the guide grooves just as they clear the overhanging arms 9, and they are held in that position in the path of the arms 10 until the sash is returned and they are picked up by 125 the arms 10, and thereafter are carried up with the sash. As they are thus moved up, the angularly or outwardly extending portions of the guide members 17 return the bracket-engaging studs 18 to their locked 130 positions underneath the overhanging arms 9.

In assembling the fixtures the shade-carrying plates are placed upon the shade spindles, and the guide studs 18 are then 135 inserted in the open ends of the guide grooves, the sash 1 being lowered so that the bracket-engaging studs 18 may be lowered to the bottom of the grooves where they are picked up by the arms 10 of the brackets. 140

The coupling between the plates of each pair when two curtains are used permits the relative angular movement necessary for making the turn in the guide grooves. This 5 turn is preferably a gradual curve, as shown, to facilitate the movement of the guide studs 18 around the turn.

It is apparent from the above that the shade-carrying plates are locked to the sash 10 and move therewith as long as the range of movement is within the vertical portions of the guide members, and that, if the sash is lowered further, the shade-carrying plates are released and left behind in the ends of 15 the grooves, and the shades are thereby lowered sufficiently for ventilation but not sufficiently to be unsightly. By these means it is a simple matter to carry two shades, and all the disadvantages resulting from 20 carrying the shades directly upon the brackets are obviated.

When the top sash and the bottom sash pass, as occurs in cleaning the windows, it is necessary to remove the bracket arms 5 25 from the top sash 1. In Figs. 8, 9, 10 and 11, I have shown a modified construction by which this removal is automatically effected, and the bracket arms are transferred from the top sash 1 to the bottom sash 19 30 as the two sashes pass. In this construction the bracket-supporting plate 20 has a vertically arranged flat spring arm 21 secured thereto at its lower end and bent outwardly at its upper end so as to form a resilient 35 bracket-holding socket open at the top. The plate-engaging part of the bracket arm 5 has a flanged base 22 forming a substantially U-shape socket-engaging part adapted to enter in the resilient bracket-holding 40 socket and surround the spring arm 21 on three sides, as shown, and removable therefrom by relative upward movement of the bracket arm, so that the bracket arm may be lifted out of the socket and is frictionally 45 held therein.

Secured on the top of the lower sash at opposite sides thereof are two bracket-removing and holding members, arranged in position to catch the bracket arms as the 50 two sashes pass, and hold them in position to be caught again by the arms 21. These bracket removing and holding members, in the illustrated embodiment, are substantially U-shape with their base secured to 55 the top of the sash by screws, and they comprise a substantially rigid outer arm or plate 23, which serves as a rigid back, and two resilient arms 24 coöperating with the rigid back 23 to form a resilient U-shaped 60 socket for the reception of the respective bracket arm. The resilient arms 24 are bent outwardly at their upper ends to provide a flaring mouth to the socket, and on their inner side they are provided with a 65 ridge or hump 25, which overhangs the

bracket arms and serves to hold them in the sockets while permitting them to be withdrawn when sufficient force is applied.

The flanged part of the bracket arms may also be provided with three arms 26 formed 70 as extensions of both the upper and lower flanges, thus providing two U-shape guides for the reception of the resilient arms 24 of the bracket removing and holding members, and to assure the entrance of these arms 24 75 into their guides, the upper ends of the resilient arms 24 may be tapered off, as shown.

It is now apparent that, when the two sashes pass within the range of the guide members 17, the bracket arms are caught by 80 the removing and holding members on the lower sash and the shade is thereby transferred to the lower sash, and the sashes may thus be freely reversed. The bracket arms are held in the removing and holding members by the friction caused by the resilient pressure of the arms 24 augmented by the overhanging ridges or humps 25, so that the shade may be moved up and down at will while it is carried by the lower sash 19. It 90 will be noted that the weight, being on the outer end of the bracket arms, tends to cause the base of the bracket arms to tilt and bind in the supporting sockets on the upper sash 1, and the attachment of the 95 brackets to the upper sash is sufficiently secure for most constructions, although the arms 21 may also have ridges or humps formed thereon corresponding to the ridges 25, if this is necessary.

It is obvious that various modifications may be made in the constructions shown in the drawings and above particularly described, within the principle and scope of my invention.

I claim:-

1. In combination with a slidable window sash and a frame therefor, a window shade carrying member, a supporting member for the window shade carrying member carried by the sash, and releasing and holding means for the window shade carrying member carried by the window frame and adapted to release the window shade carrying member from the supporting member as the sash moves in one direction and to hold the window shade carrying member in position to be picked up by the supporting member as the sash moves in the opposite direction.

2. Window shade fixtures comprising supporting brackets adapted to be carried by the window sash and open at their upper sides, a shade-carrying plate adapted to be carried by each supporting bracket, and releasing and holding means for the shade-carrying plates adapted to be secured to the window frame and to catch the shade-carrying plates as the sash descends and hold the plates in position to be picked up by the brackets as the sash ascends.

3. Window shade fixtures comprising two supporting brackets adapted to be secured to opposite sides of the window sash and each having a short overhanging arm, two shade-carrying plates arranged to receive and hold the respective shade spindles, each plate having a guide stud adapted to be supported underneath the overhanging arm of the respective supporting bracket, and releasing and holding means for the shade-carrying plates comprising two guide members adapted to be secured to opposite sides of the window frame in position to be engaged by the respective guide lugs and to guide the studs from beneath the overhanging arms as the sash descends and thereby release the shade-carrying plates from the brackets and to hold the shade-carrying plates in position to be picked up by the brackets as the sash descends.
4. Window shade fixtures comprising two supporting brackets adapted to be secured to opposite sides of the window sash and each having a short overhanging arm, two shade-carrying plates arranged to receive and hold the respective shade spindles, each plate having a guide stud provided with a guide head and adapted to be supported underneath the overhanging arm of the respective supporting bracket, and two guide members having guide grooves shaped transversely to correspond to the guide heads, the guide members being adapted to be secured to opposite sides of the window frame in such position that the flaring ends of the guide studs engage in the grooves of the respective guide members, the grooves being so shaped longitudinally that as the sash descends they guide the stud from beneath the overhanging arms and thereby release the shade-carrying plates from the brackets and hold the shade-carrying plates with the studs in the ends of the respective grooves.
5. Window shade fixtures comprising two supporting brackets adapted to be secured to opposite sides of the window sash, two guide members adapted to be secured to opposite sides of the window frame and each having an angularly extending portion, and two pairs of shade-carrying plates, one pair being adapted to engage and be guided by each guide member and to be supported on the respective supporting bracket, the two plates of each pair being coupled together to permit independent angular movement and each being arranged to receive and hold a shade spindle.
6. Window shade fixtures comprising a shade-supporting bracket including an attaching portion, attaching means adapted to be arranged on a window sash, and resilient engaging means adapted to resiliently hold the attaching portion to the attaching means

and yieldable under pressure to release the attaching portion from the attaching means.

7. Window shade fixtures comprising two shade-supporting brackets adapted to be secured to opposite sides of the upper window sash and removable therefrom by relative movement between the brackets and the sash, and two bracket removing and holding members adapted to be secured to opposite sides of the lower sash and engage the respective supporting brackets and remove the same from the upper sash as the two sashes pass.

8. Window shade fixtures comprising two bracket-supporting members adapted to be secured to opposite sides of the upper window sash, two shade-supporting brackets adapted to be attached to the bracket-supporting members by relative downward movement of the brackets and to be removed therefrom by relative upward movement of the brackets, and two bracket removing and holding members adapted to be secured to opposite sides of the lower sash and engage the respective supporting brackets and remove the same from the bracket-supporting members as the bracket-supporting members are lowered past the bracket removing and holding members and to hold the brackets in position to be again attached to the bracket-supporting members as the latter are raised past the removing and holding members.

9. Window shade fixtures comprising two bracket-supporting members adapted to be secured to opposite sides of the upper window sash, two shade-supporting brackets adapted to be attached to the bracket-supporting members by relative downward movement of the brackets and to be removed therefrom by relative upward movement of the brackets, two bracket removing and holding members adapted to be secured to opposite sides of the lower sash and engage the respective supporting brackets and remove the same from the bracket-supporting members as the bracket-supporting members are lowered past the bracket removing and holding members and to hold the brackets in position to be again attached to the bracket-supporting members as the latter are raised past the removing and holding members, and shade releasing and holding means adapted to be secured to the window frame and to extend into the path of a shade carried by the brackets and to catch the shade as the upper sash descends and hold the shade in position to be picked up by the brackets as the upper sash ascends.

In testimony whereof I have affixed my signature in presence of two witnesses.

CHARLES W. HUTCHINSON.
